UNITED STATES PATENT OFFICE.

SIMON COOPER, OF BROOKLYN, NEW YORK, ASSIGNOR TO NASHUA CARD GUMMED & COATED PAPER COMPANY, OF NASHUA, NEW HAMPSHIRE, A CORPORATION OF MASSACHUSETTS.

MACHINE FOR MAKING REINFORCED PAPER.

1,183,437.

Specification of Letters Patent.

Patented May 16, 1916.

Application filed April 14, 1915. Serial No. 21,315.

To all whom it may concern:

Be it known that I, SIMON COOPER, of Brooklyn, in the county of Kings and State of New York, have invented certain new 5 and useful Improvements in Machines for Making Reinforced Paper, of which the following is a specification.

This invention relates to the manufacture of reinforced sheet material, and especially 10 concerns mechanism or machinery whereby both longitudinal and transverse strands may be secured between two webs of sheet material. For convenience of description I shall hereinafter refer to the sheet material 15 as paper and to the strand material as twine. It is to be understood, however, that I do not limit myself to these particular materials.

One of the objects of my invention is to 20 provide a machine which will manufacture a loosely woven fabric of twine, and combine this fabric with two layers or webs of paper, using a coating of glue or other suitable adhesive to unite the whole.

25 Another object of the invention is to provide a machine which embodies what might be termed an attachment, or a complement, to a regulation loom, the shuttle of the loom supplying the transverse twine while the 30 longitudinal reinforcing twines are controlled by the loom, harness and reed mechanisms to supply the reinforcement to the paper as a true woven fabric, although very loosely woven.

35 With these and other objects in view my invention consists in the improvements which I shall now proceed to describe and claim.

Of the accompanying drawings: Figure 1 40 is a side elevation, partly broken out or in section, illustrating my improvements as applied to or connected up with a regulation loom, said figure showing no more of the loom than is necessary to an explanation of 45 my improvements. Fig. 2 represents an elevation from the right of Fig. 1, but broken out to reduce the width of the figure. Fig. 3 is a detail elevation of the loom reed, the wires being spaced differently from the 50 usual spacing in a loom. Fig. 4 represents a detail section on line 4—4 of Fig. 1. Fig. 5 is a detail side elevation of one of the twine carrying chains. Fig. 6 represents a section on line 6—6 of Fig. 5. Fig. 7 is a

detail elevation of one of the latches or 55 twine guiding devices.

Similar reference characters indicate similar parts in all of the views.

Referring first to Figs. 1 and 2, a portion of the frame of a suitable loom is indicated 60 at 12, said loom having its usual lay 13, reed 14, and a beam 15. The warps which become the longitudinal strands of my reinforcement are indicated at a. It is to be understood, of course, that the alternating 65 warps a are shifted vertically by the usual harness mechanism so that the shuttle on the lay 13 will cause the filling twine to produce, with the warps a, a woven fabric. It may be explained here, however, that I do 70 not employ the reed mechanism to beat up in the ordinary sense, but only to carry the weft or transverse twine to position to be taken by grippers hereinafter described and carried along to the nip of the rolls which 75 combine the paper with the loosely woven fabric.

Mounted in a suitable frame 16 are upper and lower rolls 17, 18, which I term the combining rolls. They are mounted respectively in bearings 19 and 20. At each end of the roll 17 is a sprocket 21.

Secured to the beam 15 of the loom are two brackets 22 which overhang the point to which the lay 13 is swung by its usual 85 mechanism to "beat up," such position being indicated by full lines in Fig. 1. These full lines compared with the dotted lines simply conventionally indicate the swing of the lay. Pivotedly mounted in the overhanging end or portion of each bracket 22 is a bracket 23, the pivot being indicated at 90 24. Said pivot is practically a rock shaft, and it has an arm 25 to which is connected one end of spring 26, the other end being 95 secured to a suitable fixed point. Rotatably mounted in each pivoted bracket 23 is a small sprocket 27. A chain 28 is mounted on each pair of sprockets 21, 27, a suitably mounted adjustable idler being indicated at 100 29. The length of the links of the two chains 28 control the spacing of the lateral or transverse strands or twine, the said twine being carried or "beat up" by the reed of the loom to position where they will be 105 gripped or nipped by the adjacent diverging ends of the chain links as they pass over the sprockets 27, the filling twine being re-

leased again as the chains pass around the sprockets 21. Referring particularly to Figs. 5 and 6, it will be seen that the alternating links of the chain are wide and 5 narrow. While one link has a relatively wide lug 30, the two next overlapping links pivoted thereto at 32, have relatively narrow lugs 31. These lugs are so formed as to preferably slightly overlap at their ends 10 when the chain is traveling straight, and consequently when twine is introduced between the diverging ends of the lugs as indicated in Fig. 1, then when these ends forming jaws close up because of the continuous traveling movement imparted to 15 the chains, the twine will be gripped or nipped between the one end of a lug 30 and the adjacent ends of the lugs 31. To avoid the liability of severing the twine the corners of the lugs are preferably rounded as 20 indicated in Fig. 6. In order that the sagging of the lower stretches of the chains shall not open the jaws or nippers and consequently release the filling twine until it is 25 time to be released, I provide guide strips 33 which may be mainly supported by the beam 15 of the loom and connected thereto, and which may also be connected to the frame 16 so as to practically act as ties to 30 hold the loom and the frame 16 properly spaced. The supports or connections for these strips 33 with the frame 16 may comprise stud pins 34 indicated in Fig. 2.

In Fig. 1 I indicate three idler guide rolls 35, 36, 37. An upper strip or web of paper *b*, leading from any suitable reel not necessary to illustrate, passes over idler 35 and around the upper roll 17. Another strip or web of paper *c* leads from any suitable 35 reel, over the idler 36, and under and around lower combining roll 18. The idler 37 simply guides the combined sheets and the reinforcement out from the machine. As the lower web *c* passes under the roll 18, 40 it receives a coating of glue or other suitable adhesive from a roll 38 which is supplied with adhesive by a suitable pan 39. The shaft of the roll 38 is mounted in bearings 40 which are vertically adjustable to 45 enable the attendant to quickly separate the glue roll from the paper, especially when the machine stops running, so that the paper will not stick to the glue roll. This adjustment of the glue roll is effected by 50 providing a vertical screw 41 which engages the lower portion of each vertically adjustable bearing 40, each screw 41 being mounted in bearings 42, between which 55 bearings is located a nut 43 fitting the threaded portion of the screw. The nut carries a worm wheel 44 which is actuated by a worm 45 carried by a shaft 46 having one or more hand wheels 47. The attendant, by rotating shaft 46 can quickly lower 60 the glue roll or return it to position. 65

To enable the combining rolls to be quickly separated either for the introduction of the webs or for any other purpose, I mount the upper roll 17 in vertically adjustable bearing blocks 48. Extending under each bearing block 48 is an eccentric 49 carried by a shaft 50 having a handle 51. By means of the two handles the eccentric 49 can be quickly actuated to lift the bearing blocks 48 and so raise the upper roll 17. 70

To facilitate the entrance of each stretch of filling material between the chain grippers, I provide guides 52, one at each side of the machine. For convenience of description I have termed these guides latches. 80 Each guide or latch swings, being pivoted at 53 to a short arm of pivoted bracket 23. It has a curved face 54 and a hook or toe 55, and is normally held in the position indicated in Fig. 1 by a spring 56 (see also Fig. 85 7) a suitable stop 57 limiting the forward position of each latch or guide. When the lay of the loom swings forward the reed carries the strand just left by the shuttle either against the lower faces of the lugs 90 of the links, or against the curved face of the guide 52, or simultaneously between the two, the reed moving to position to carry the strand just under the hook or toe 55. In order that the reed may reach the position indicated by full lines in Fig. 1, a pair of reed wires at each end are spread as indicated in Fig. 3. In other words, at each end of the reed a wide enough opening is left to momentarily receive the small sprocket 27 100 and the two or three links of chain passing around that sprocket. After the shuttle has been received in its box at one end of the lay, and the reed has "beat up" and swung away, the next pick of the shuttle 105 causes the filling thread to be looped under hook or toe 55 of the guide or latch at that side of the machine, and the traveling chain causes two link ends to bite that loop of the twine and carry it along. When the shuttle is given the next pick and traverses to the other end of the lay, a similar operation is effected in connection with the guide or latch at the other side of the machine. By 110 the time the shuttle has returned to the position first-mentioned, the traveling chains have carried the loop along and released it from the swinging guide or latch. 115

It will now be seen that I have provided a machine for making reinforced paper in which combining rolls act as means for causing the paper to travel in the direction of its length. The loom mechanism furnishes means for making a complete fabric while the operation of the carrying or transferring chains 28 causes the fabric to be loose woven. The lugs 30, 31, of the chains or rather the ends of those lugs constitute jaws or grippers which grasp edge portions of the fabric, inasmuch as the portions of 120

the transverse strings which are taken off by said jaws or grippers are practically at the edge of the fabric. These traveling grippers transfer the fabric in loose woven condition to the combining rolls which take the fabric from the grippers and combine it with the paper.

As has been explained, each bracket 23 is pivotally mounted on a bracket 22. The object of this is that, in case the shuttle should fail to go into its place at one end of the lay, and should be forced against the bracket 23 by the reed of the loom, said bracket 23 can swing back on its pivot without damage to the machine. This is an important feature of my invention because the action of the shuttle just described is liable to occur frequently.

It is to be understood that the chains 28 are driven continuously, and that when the next of the adjacent links acting as jaws have gripped the twine, the chains have moved far enough to advance them the distance of one link by the time the shuttle has been shot over to the other side of the loom. The twine which has been held in the hook or toe 55, is automatically removed from said hook after having been held in position while the chain 28 is advancing to guide the loop of the twine at the proper height into the next succeeding jaw space of that particular chain.

Having now described my invention what I claim is:

35 1. A machine for reinforcing paper with twine, including the lay and reed of a loom, means for combining two webs of paper, and means for transferring twine from the position to which it is shifted by the reed, 40 to position between and transverse of the webs of paper.

2. A machine for reinforcing paper with twine, including the lay and reed of a loom, means for combining two webs of paper, 45 and means for transferring twine from the position to which it is shifted by the reed, to position between and transverse of the webs of paper, said transferring means comprising a pair of chains having grippers to hold and carry the twine.

3. A machine for reinforcing paper with twine, including the lay and reed of a loom, means for combining two webs of paper, 55 and means for transferring twine from the position to which it is shifted by the reed, to position between and transverse of the webs of paper, said transferring means comprising a pair of chains provided with lugs having end faces to coöperate in gripping the twine.

4. A machine for reinforcing paper with twine, including the lay and reed of a loom, means for adhesively combining two webs 60 of paper, and means for transferring twine from the position to which it is shifted by

the reed, to position between and transverse of the webs of paper.

5. A machine for making reinforced paper, comprising means for causing previously manufactured paper to travel in the 70 direction of its length, means for making a complete loose-woven fabric, and means for uniting said fabric with the paper.

6. A machine for making reinforced paper, comprising means for causing paper 75 to travel in the direction of its length, means for making a complete loose-woven fabric, traveling grippers for grasping edge portions of the fabrics, and means for taking the fabric from said grippers and 80 combining it with the paper.

7. A machine of the character described comprising a pair of combining rolls for two webs of paper, means for applying an adhesive to one of the webs, means for making 85 a loose-woven fabric, and traveling grippers for grasping edge portions of the fabric and drawing it to and between the rolls and the paper thereon.

8. A machine for making reinforced paper comprising a loom mechanism for supplying longitudinal and transverse strands in the form of a loose-woven fabric, means independent of the loom mechanism for combining said fabric with paper, and 95 means for transferring the fabric from the loom mechanism to said combining means.

9. A machine for making reinforced paper comprising a loom mechanism for supplying longitudinal and transverse strands 100 in the form of a loose-woven fabric, means independent of the loom mechanism for combining said fabric with paper, and means for transferring the fabric from the loom mechanism to said combining means, 105 said transferring means comprising two endless series of grippers.

10. In a machine of the character described, a pair of chains mounted on rotary supports, the links of said chains having 110 coöperating jaws adapted to open and close as they pass onto and from their supports, means for introducing twine in taut condition to the jaws at one end of their travel, and means for combining the twine 115 with paper at the other end of the travel of the jaws.

11. In a machine of the character described, a pair of chains mounted on rotary supports, the links of said chains having 120 coöperating jaws adapted to open and close as they pass onto and from their supports, means for introducing twine in taut condition to the jaws at one end of their travel, guides for directing the twine between said 125 jaws, and means for combining the twine with paper at the other end of the travel of the jaws.

12. In a machine of the character described, a pair of chains mounted on rotary 130

supports, the links of said chains having coöperating jaws adapted to open and close as they pass onto and from their supports, means for introducing twine in taut condition to the jaws at one end of their travel, and means for combining the twine with paper at the other end of the travel of the jaws, means being provided for preventing the jaws from releasing the twine until they 10 reach the combining means.

13. The combination with the lay of a loom, of means for combining two sheets of paper, endless transmitters for carrying the twine furnished by a shuttle on said lay to 15 the combining means, and yielding supports for said transmitters to prevent damage resulting from the swing of the lay.

14. The combination with the lay of a

loom, of means for combining two sheets of paper, endless chains provided with jaws 20 for gripping twine furnished by a shuttle on said lay and carrying the twine to the combining means, means for driving said chains continuously, a pair of hooks for temporarily holding the twine while the 25 shuttle is shot over the lay, and means whereby the twine is permitted to be automatically released from said hooks as the jaws of the chains move away from the hooks.

In testimony whereof I have affixed my signature, in presence of a witness.

SIMON COOPER.

Witness:

MARY H. LEWIS.
